UNITED STATES PATENT OFFICE.

GRAFTON E. LUCE, OF CHICAGO, ILLINOIS, ASSIGNOR, BY MESNE ASSIGNMENTS, TO
CHARLES A. BROWN, OF HINSDALE, ILLINOIS.

METHOD OF AND MEANS FOR BURNING BRICKS.

Application filed July 25, 1917. Serial No. 182,653.

To all whom it may concern:

Be it known that I, GRAFTON E. LUCE, a citizen of the United States, residing at Chicago, in the county of Cook and State 5 of Illinois, have invented a certain new and useful Improvement in Methods of and Means for Burning Bricks, of which the following is a full, clear, concise, and exact description, reference being had to the accompanying drawings, forming a part of 10 this specification.

My invention relates to a method of and means for burning bricks. This invention is an improvement upon a process of burning 15 bricks known in the art as the Lambert process. In that process a generally horizontal zone of heat is created in the lower part of the kiln at a rapid rate so as to drive off the moisture from the bricks faster 20 than the kiln draft will carry the same off so that finally the draft becomes choked and the heat which has been put in the bottom of the kiln is held there and is not dissipated by leakage of air or by any draft.

25 The present invention is particularly concerned with an improved manner of generating the heat in the bottom of the kiln; in an improved manner of applying and burning fuel in the kiln, and in an improved 30 manner of causing the heat which is generated in the lower part of the kiln to be moved through the unburned part of the kiln to finish the entire kiln.

Further objects of the invention are to 35 provide an improved structure of kiln for carrying out the various steps of the process and a new relation between a particular type of firing apparatus and a brick kiln.

Other incidental and contributory objects 40 will be apparent from the following specification, which, together with the drawings which form a part of the same, describe one particular manner of practicing and constructing my invention so that those skilled 45 in the art may fully understand the same.

Figure 1 is a cross sectional view of a kiln of bricks with parts broken away with the burning apparatus applied in position to create a zone of heat in the lower part of 50 the kiln. This section of Figure 1 is taken through an arch of the kiln.

Figure 2 is a similar view showing the blower pipe in position during the stage of blowing.

55 Figure 3 is a fragmentary section taken

on the line 3, 3 looking in the direction of the arrows showing the disposition of the blower pipe in the lower furnace and showing the relative arrangement of dog-house and arch. 60

The bricks are preferably formed with a compact exterior and somewhat less compact interior which will permit of rapid firing without damage. The bricks are then set into the kiln for burning. The bricks may 65 be formed in any other desired manner, as this feature forms no part of the present invention. The type of kiln which I prefer to employ is the scooved kiln although it is to be understood that the invention is applicable to other forms of kilns. In building a kiln, a bed or foundation of previously 70 burned bricks three layers deep, as shown by the reference, numeral 1 is first laid down flat on the ground. This layer of burned 75 bricks 1 is interrupted to form a space or furnace 2 substantially three bricks thickness deep and about $\frac{1}{4}$ of a brick length in width extending completely across the kiln. This furnace is closed off at the top by a series of 80 burned bricks being placed close to each other with small spaces between them. They are set, however, substantially in contact with each other. The bricks to be burned are then piled on top of the lower layer 1 85 with arches formed over the furnaces 2 and the bricks 3. The dried bricks which are to be burned may be handled by cranes or in any other manner. If a crane is employed 90 the bricks are taken from the driers on cars 90 piled eight brick widths deep and the cranes pick up a carload at a time and place it in the proper position for building up the kiln.

A crane load of bricks is set on each side 95 of the burned bricks 3 resting upon the foundation of burned bricks 1, as shown in Figure 3. This leaves an opening which becomes the arch opening forming a furnace above the furnace 2 and communicating 100 with the furnace 2 by means of the spaces 4 between the bricks 3 as well as through the crevices between the green bricks 5 at the bottoms of the arches and the burned bricks 1 which form the foundation. 105

The workmen with their hands draw the upper layers of bricks over to form "jets" 6 and thus close off the tops of the arches 7. After the arches are formed the spaces behind the jets are filled in with extra bricks

placed by hand as shown at 8. To complete the kiln the unburned bricks are packed on top of the bricks thus set by means of the crane where the same is employed until the kiln is completed.

I prefer to form the kilns of about 22 arches set 48 courses high measured in brick widths exclusive of the bottom bricks 1. The width of the kiln at the bottom is about 10 54 brick lengths and at the top is about 51 brick lengths. Each pillar or leg between the arches has a horizontal thickness of about four brick lengths and each arch is about 15 2 brick lengths in width so that the consecutive arches are about six brick lengths distance from center to center.

The bricks all stand on edge criss-cross with narrow spaces between them with a spacing of about 3 over 1.

20 On the outside of the kiln above the arches and on the ends of the kiln from the ground up there is placed a wall 9 of "double coal" bricks, the thickness of this wall being equal to the length of a single brick. The double 25 coal bricks in this wall are made up by mixing coal screenings, preferably anthracite coal with the clay in the proportion of about 80 lbs. to a thousand bricks.

Outside of the double coal brick wall 9 a 30 wall of previously burned bricks 11 is built up all around the sides and end of the kiln. This wall 11 has a thickness of a brick length for the lower half and has a thickness of a single brick width for the upper 35 half. The outside of the wall 11 is then daubed over or "scoved" with a daubing made of sand and loam so as to close the cracks between the bricks. On top of the kiln a layer 12 of previously burned bricks 40 which is called the platting or flatting is laid with the bricks lying on the side. These bricks are laid closely but are not scoved or daubed and the cracks or fissures between them permit the gases and vapors from the 45 kiln to escape.

The outside wall 11 of burned brick is built across the upper part of the ends of the arches 7 as can be seen at 13 in Figs. 1 and 2, but so as to leave openings to the 50 exterior along the lower parts of the arches 7. Extensions 14 called "dog-houses" are built out from the open end of the side wall 11 in line with the arches.

Above each dog-house a peep hole 15 is 55 left in the wall 11, this peep hole being normally closed by a brick bat.

The side and end walls of the kiln may be suitably braced as desired.

Some means is preferably provided for 60 indicating the settle. This may consist of a rod or finger normally touching the top of the platting or a pile of brick bats on top of the platting as for instance a rod hung from the roof or frame work of the shed, the end 65 of the rod just touching the flatting or a pile

of brick bats on the flatting so that when the settle begins a space will show between the end of the rod and the top of the kiln.

For the purpose of heating the bricks for firing the same I provide a horizontal burner 70 nozzle 16 at each end of each arch. This nozzle comprises a horizontal tube terminating in a restricted tip or jet 17 having a conical flange 18 about the same. A pipe 19 adapted to deliver powdered coal in proper 75 quantities communicates with the nozzle 16 by way of an opening 20 above which the pipe 19 is adjustably secured. The pipe 19 telescopes with a pipe 21 from which it is supported and to which a supply of powdered 80 coal is furnished. The adjustment of the pipe 19 may be fixed as by means of the thumb screw 22. The opening 20 has a flange 27 about the same to insure catching of the stream of powdered coal from the pipe 19, 85 and to admit air which is drawn in by the blast which is supplied to the nozzle 16 from any convenient source. The blast of air in the nozzle 16 may be generated by means of a fan, a rotary blower, by a steam jet en- 90 training air or other well known means.

For the purpose of blowing in air at a certain pressure in carrying out the latter part of the process of my invention as I shall describe hereafter, I provide a blower 95 pipe 23 which consists of a straight length of pipe extending from end to end of the space 2 and having openings 24 substantially evenly distributed across the width of the kiln for blowing air under pressure into the 100 kiln as will be described presently. The end of the nozzle 16 is adapted to register with the open end of the blower pipe 23.

The pipe 23 may consist of one continuous piece from side to side of the kiln or 105 may consist of separate parts inserted from each end and furthermore the section of the pipe may be decreased to take care of the different amounts or quantities of air flowing therethrough.

I shall now describe the manner of firing the kiln in the manner previously described. The nozzle 16 is directed into the lower furnace 2 which has its walls made up entirely of 110 burned bricks. A blast of air is then directed through the pipe 25 and at the same time the proper quantity of powdered coal is fed through a pipe 19 and these two elements unite in a stream or blast in the nozzle 16 which is directed into the lower furnace 2. The blast of powdered coal and air is ignited as by means of a shovel full of 115 live coals, a piece of burning oil soaked waste, or the like.

The powdered coal is of a fineness such 125 that approximately 85% will pass through a 200 mesh screen and 95% through a 100 mesh screen. The powdered coal is retained in a very dry condition having only about 1 per cent moisture.

The fire is directed into the furnace 2 from each end thereof with as great a force as is required to fill the furnace. This burning is continued for about 2 hours and at 5 the end of that time the entire furnace 2 will be heated across the length of the arch. The bricks 1 and the layer of bricks 3 will be red hot and the adjacent green bricks 5 will have been dried off and partially burned 10 by this preliminary heating of the burner 2. The face of all the bricks facing the inside of the arch will also have been dried off so that at the end of this time the arch is thoroughly dry and the legs or benches will 15 have a preliminary drying which will permit them to be burned very rapidly.

The advantage of burning in a furnace of burned bricks is that the fire burns clearer and hotter from the very beginning and 20 there is no tendency for the ash or particles of coal to adhere to the walls. After the furnace 2 has been properly heated up so as to dry off the furnace which is formed by the arch 7, the nozzle 16 is raised into 25 the dotted line position 26 shown in Figure 1, the pipe 19 being raised and fixed in position to correspond and the flame is then directed into the furnace 7 above the furnace 2.

30 The fire is then directed to heating the arch completely across the bottom of the kiln to substantially a brick-burning heat in the neighborhood of 2000 degrees F. The advantage of the coal burning apparatus here- 35 tofore described is that no outlet or regular draft is necessary as is the case where lump coal is burned. It is possible to burn the powdered coal under a very considerable pressure in a substantially closed place so 40 long as the blast is maintained. This is due to the fact that the blast which carries in the fuel is also sufficient to form a complete combustion of the fuel thus carried. In order to burn powdered coal a very 45 considerable length of fire box is necessary and this is completely and adequately provided in the arches by the furnaces 2 and 7.

The fire is first directed to igniting the double coal bricks 9 and then to heating 50 the arch evenly throughout its entire length. This is accomplished in about 16 hours of burning.

The condition desired by the burners is to secure an even heat in a continuous zone 55 throughout the entire bottom of the kiln, this zone rising slightly at the edges where the double coal bricks 9 have been ignited.

The fire is forced to such an extent and must be forced to drive off the moisture of 60 the bricks faster than the kiln draft will carry it off so that the top of the kiln finally becomes choked with steam, forming what I term a blanket of steam. The formation of the blanket of steam together 65 with the pressure generated by the nozzle

16 tends to insure the creation of the isothermal zone in the bottom of the kiln. The employment of the powdered coal as fuel is not detrimental as might be expected because of the very fact that the kiln draft 70 has been shut off by this choking with steam and as a consequence the ash does not pass up through the stack and settle upon the green brick but instead is trapped in the relatively dead air space in the arches 75 or furnaces 7 so that practically no inconvenience is occasioned by the ash. The ash is not driven from the top of the kiln and consequently no objection can be made to burning bricks in proximity to dwellings or 80 other buildings.

At the end of about 16 hours the operator can notice a slight settle at the top of the kiln, this settle being substantially even entirely across the kiln if the fire has been 85 properly maintained. This is an indication that the bricks have shrunk due to partial burning and also that the bricks in the bottom of the kiln are sufficiently softened to permit of a slight crushing together. The 90 fires are then shut off. The pipes 23 are then introduced in the furnace 2 and the nozzles 16 brought into alignment with the pipes and great quantities of air are blown into the pipes 23. The amount of air blown 95 in is sufficient to fill the bottom of the kiln taking the place of the air previously heated and expanded by combustion and at a pressure sufficient to overcome the resistance of the blanket of steam in the upper part of 100 the kiln. This blast of air levitates or raises the blanket of steam forcing it up at the top of the kiln and at the same time it carries upward the heat under the blanket of steam thereby finishing the bricks in the 105 strata above. This blowing is continued until the zone of heat is carried upward under the blanket of steam to the very top of the kiln and then out. At this point the blowing 110 is discontinued.

It is to be noted that the initial blast of cold air does not strike the heated bricks which are being burned for the first time but strikes only the heated bricks 1 and 3 which were previously burned and which are 115 not subject to cracking. The blast of air finding its way to the narrow openings and crevices between the bricks 3 and between the bricks 1 is heated sufficiently that it does not chill the bricks 5 around the arches and 120 consequently there is much less danger of cracking or damaging any of the bricks in the arches or other parts of the kiln.

The result of this blast of air is to levitate or raise the blanket of steam forcing it out 125 of the top of the kiln. As the blanket of steam is raised the heated zone is carried upward and as the blowing continues the heated zone travels throughout the rest of the kiln to the top of the same and burns the 130

bricks to the desired degree as it passes. When the wave or zone of heat has reached to top of the kiln the bottom of the kiln is practically cool enough for handling. 5 This blowing continues for about 24 more hours making the total time of burning in the neighborhood of 40 to 48 hours from the beginning of burning.

The fuel cost is very low because of the 10 short period during which burning is carried on and because of the low cost of powdered fuel.

After the blowing has been completed, that is, after the zone of heat has traveled 15 to the top of the kiln, the dog-houses are knocked down and the air is allowed to enter to cool off the kiln. As a result the kiln may be taken down and hauled away very shortly.

20 In firing the kiln it is essential to observe the following condition. The firing must be rapid enough and must be distributed over sufficient bricks to evolve the blanket of steam. Otherwise the heat will 25 escape by the kiln draft and will not be available for blowing.

At the same time sufficient bricks must be heated so that they contain a large enough body of heat to finish the rest of the kiln. 30 With these conditions observed burning of a kiln of bricks is under the absolute control of the operator at all times.

The arches or furnaces provide large free 35 space within which the flame from the powdered fuel may be developed. The formation of the blanket of steam which shuts off the draft does not prevent the burning of the powdered fuel as it is supplied with its own air for supporting combustion, and 40 hence does not require any definite draft as would be the case in burning lump fuel.

The extent of the fire may be restricted and the fuel consumption may be restricted and at the same time the pressure in the 45 kiln which contributes the heat may be retained merely by the addition of a surplus of air. Thus it is possible within the furnaces, that is within the arches to vary the total amount of heat generated without 50 varying the pressure which is necessary to distribute the heat. This is of very great importance in obtaining the heated zone in the lower part of the kiln.

When the fire is directed into the furnace 55 7 it is to be noted that no separate fire box is necessary and the heat is intimately distributed among the bricks and directly applied. The arch thus serves the double function of permitting the generation of a 60 long flame and of being a place for the deposit of the ashes which settle due to the lack of upward current. A further advantage over the burning of lump coal is that the direct radiation from the fire which results 65 in burning lump coal is distributed through-

out the length of the flame in my process and hence the bricks directly at the ends of the arches are not overburned before the heat can be driven through the interior of the kiln.

The fire may be forced from the very beginning on account of the distributed nature of the same and this tends to secure quick and even burning.

In burning according to my method and employing powdered coal, there is practically no draft in the arch or furnaces proper, therefore none of the ash of the powdered coal would be carried up into the kiln where the bricks are green and this prevents any choking of the kiln with ash or any detrimental effect on the coal before or at the time of burning.

I claim:

1. In a kiln, a stack of green bricks and a foundation of burned bricks, said foundation of burned bricks having a furnace therein and said stack of green bricks having a furnace therein adjacent the furnace in the foundation, said furnaces being connected at intervals through a foraminous wall of burned bricks.

2. In a kiln, a transverse arch of green bricks, and a transverse furnace of burned bricks lying parallel with said arch and communicating through spaced relatively narrow slots with said arch.

3. In a kiln, a foundation having a transverse groove therein, forming a furnace within which to burn fuel, a series of bricks set on edge over the top of said groove partially closing the same off and an arch of green bricks set over said groove and communicating with said groove through the interstices between the bricks set on edge and through the interstices between the bricks in the foundation.

4. In a kiln, a foundation having a transverse groove therein, a series of bricks set on edge over the top of said groove partially closing the same off and an arch of green bricks set over said groove and communicating with said groove through the interstices between the bricks set on edge and through the interstices between the bricks in the foundation means for burning fuel in said groove and in said arch and a pipe adapted to be inserted in said groove, said pipe having means for creating a blast of air and having a plurality of openings for discharging said air blast at a plurality of points along said groove, said pipe being adapted to be put in communication with the means for burning fuel.

5. The herein described method of burning bricks, which consists in forming a kiln of the bricks with a main transverse arch at the bottom, and a secondary arch or furnace below the main arch formed of burned bricks, introducing combustible fuel into the

secondary arch of a kind and in sufficient quantity to very rapidly raise the temperature of the walls of the secondary furnace to a high temperature, approximately 2000°
 5 Fah., thereby applying heat to the bricks forming the walls of the main arch with sufficient rapidity to thoroughly dry them preparatory to burning in such a short time as to form a steam blanket in the upper part
 10 of the kiln, then introducing fuel into the main arch to burn the lower part of the kiln, then introducing air into the secondary furnace in sufficient quantities to levitate the steam blanket and the zone of heat formed
 15 about the main arch, thereby burning the rest of the bricks.

6. In a kiln, a transverse arch of green bricks, a foundation of burned bricks, the foundation of burned bricks having a furnace therein, and a slotted floor of burned bricks dividing said furnace from said arch.

7. In a brick kiln, a transverse arch of green bricks, a furnace having walls of burned brick extending longitudinally beneath the arch, said furnace divided from the arch by a floor of burned bricks spaced apart to form narrow communicating slots.

8. In a brick kiln, a transverse arch of green bricks, a furnace extending longitudinally beneath the arch in which to burn fuel, the wall between the furnace and the arch provided with narrow spaced slots whereby the arch bricks are protected from the intense heat developed in said furnace.

35 9. In a brick kiln, an arch of green bricks, a furnace of relatively small cross section extending longitudinally beneath said arch, a wall of burned bricks substantially confining the heat of combustion to said furnace, said wall being provided at intervals with narrow slots for the escape of the products of combustion from the furnace to said arch.

40 10. In a brick kiln, an elongated furnace adapted to have fuel projected into same from both ends, an arch of green bricks extending above the furnace, and an arch

floor of burned bricks, dividing the furnace from the arch, said floor formed of bricks resting at their ends on the side walls of the 50 furnace and spaced slightly apart, forming narrow communicating slots between the furnace and the arch above same.

11. The method of burning bricks which comprises introducing heat at a predetermined place in a foraminous pile of bricks, and after the surroundings of the heated place have been heated to a predetermined degree, transferring the heating to another location in the surrounding heated zone having more extensive communication with the entire pile.

12. The method of burning bricks with powdered fuel without choking the kiln, which comprises building a small furnace 65 below a large furnace, heating by means of the small furnace until the walls of the large furnace are hot enough not to collect soot from the zones of incomplete combustion in the flame, and then transferring the 70 heating to the large furnace.

13. The method of burning bricks, which comprises building a small furnace adjacent a large furnace, burning the large furnace partially by heating the small furnace, 75 burning the lower part of the kiln by heating the large furnace, and burning the upper part of the kiln by blowing air through the lower burned portion to carrying the heat up.

14. The method of burning bricks, which comprises building a small furnace adjacent a large furnace, burning the large furnace partially by heating the small furnace, burning the lower part of the kiln by heating the large furnace, and burning the upper part of the kiln by blowing air through the lower burned portion to carry the heat up, said air being introduced into the small furnace, to avoid damage to the bricks forming the large furnace by too sudden cooling.

In witness whereof, I hereunto subscribe my name this 20th day of July, A. D. 1917.

GRAFTON E. LUCE.
